UNITED STATES PATENT OFFICE

148,298

DESIGN FOR A GAME IMPLEMENT

James W. Harvey, Lakeville, Conn.

Application October 4, 1945, Serial No. 122,534

Term of patent 14 years

(Cl. D34—5)

To all whom it may concern:

Be it known that I, James W. Harvey, a citizen of the United States of America, residing at Lakeville, Litchfield County, and State of Connecticut, have invented a new, original, and ornamental Design for a Game Implement, of which the following is a specification, reference being had to the accompanying drawing forming part thereof.

Fig. 1 is a front view of a game implement, embodying my new design.

Fig. 2 is an edge view of the same.

The implement has a central handle and at one end an elongated frame member having a shallow flexible catching net and at the other end a similarly shaped batting member.

I claim:

The ornamental design for a game implement, substantially as shown and described.

JAMES W. HARVEY.
